UNITED STATES PATENT OFFICE.

WILLIAM E. WHITEHURST, OF MIDVILLE, GEORGIA.

WINDOW SHADE.

Application filed October 10, 1922. Serial No. 593,509.

To all whom it may concern:

Be it known that I, WILLIAM E. WHITEHURST, a citizen of the United States, residing at Midville, in the county of Burke and State of Georgia, have invented new and useful Improvements in Window Shades, of which the following is a specification.

In carrying out the present invention it is my purpose to provide a window shade which will be constructed in such manner that the same may be raised and lowered without employing the usual spring roller and which, when in lowered position, will cover the entire window, while when in raised position the lower half of the window will be opened and the top half only covered.

It is also my purpose to provide a window shade which will embrace the desired features of simplicity, efficiency and durability, which may be manufactured and marketed at small cost and which will embody comparatively few parts, and these so arranged and correlated as to reduce the possibility of derangement to a minimum.

With the above recited objects in view, and others of a similar nature, the invention resides in the construction, combination and arrangement of parts set forth in and falling within the scope of the appended claims.

In the accompanying drawings:

Figure 1 is a front elevation of a window shade constructed in accordance with my invention and applied to a window, the shade being shown in open position.

Figure 2 is a sectional view on the line 2—2 of Figure 1.

Figure 3 is a similar view to Figure 1, showing the shade in closed position.

Figure 4 is a vertical sectional view on the line 4—4 of Figure 3.

Figure 5 is an enlarged view showing one of the bearings for the rollers.

Figure 6 is a sectional view on the line 6—6 of Figure 5.

Referring now to the drawings in detail, 1 and 2 designate rollers arranged respectively at the top and center of a window frame, clearly shown in Figures 1 and 3 of the drawings. Each roller 1—2 is journaled at its ends in bearings 3. In the present instance, each bearing 3 comprises a base 4 formed with openings 5 through which

passed in order to fasten the bearing to the window frame. Outstanding from the base 4 is a circular head 6 having its inner side formed with an opening 7 and with a counter-sunk recess 8 at the center of the inner wall of the opening 7. The opening 7 at the juncture of the circular side wall and end wall is formed with a race-way 9. The end of the roller that fits into the opening 7 is formed with a disk-like enlargement 10 that fits into the opening 7, while the outer end of the roller is circumferentially reduced, as at 11, and fits into the counter-sunk recess 8, as clearly shown in Figure 6 of the drawing. The marginal edge of the enlargement 10 contiguous to the race-way 9 is formed to provide a race-way 12 and within these race-ways are mounted anti-friction balls 13 that enable the roller to revolve freely within the bearing members. These bearing members support the rollers 1 and 2 in proper positions at the top and center of the window frame. Trained over the rollers 1 and 2 is an endless shade section 14 having an inner run 70 that lies next to the window frame and an outer run that is arranged beyond the inner run, clearly shown in Figures 2 and 4 of the drawings. Stitched or otherwise secured to the inner run of the endless shade section 14 at one end thereof is a shade section 15. The lower end of the shade section 15 is stiffened by the usual strip 16 that is equipped with a finger pull 17. The end of the outer run of the shade section 14 remote from the end of the inner run to which the shade section 15 is secured is provided with an eyelet 18 from which depends a cord 19 equipped at its lower end with a finger ring 20.

In practice, when it is desired to close the shade the finger pull 17 is pulled down, thereby lowering the sections 15, and in the downward movement of the sections 15 the endless shade section 14 rotates about the 100 rollers 1—2 so that the section 15 may be pulled down, as shown in Figures 3 and 4 of the drawings. When it is desired to raise the section 15 a pull is exerted upon the ring 20, thereby reversing the direction 105 of rotation of the section 14, so as to raise the shade section 15 to the position shown in Figures 1 and 2 of the drawings.

I have entered into a detailed description of the construction and relative arrangement 110

of parts embraced in the present and preferred embodiment of my invention with a view to imparting a full, clear and exact understanding of the said embodiment. I
5 do not desire, however, to be understood as confining myself to the said specific construction and relative arrangement of parts, inasmuch as in the future practice of my invention such changes or modifications may
10 be made as fairly fall within the scope of my invention as defined by my appended claims.

Having thus described the invention, what is claimed as new, is:—

- 15 1. In a window shade, rollers mounted at the top and center, respectively, of the window frame, an endless shade section on said rollers, a second shade section secured to the inner run of the first mentioned section at one end thereof and a pull ring secured to the outer run of said endless shade section at the relatively opposite end thereof.
- 20 2. In a window shade, rollers mounted at the top and center, respectively, of the window frame, an endless shade section on said rollers, a second shade section secured to the inner run of the first mentioned section at one end thereof, a pull ring secured to

the outer run of said endless shade section at the relatively opposite end thereof, and antifriction bearing members supporting the ends of each of said rollers.

3. In a window shade, rollers mounted at the top and center, respectively, of the window frame, an endless shade section on said rollers, a second shade section secured to the inner run of the first mentioned section at one end thereof, a pull ring secured to the outer run of said endless shade section at the relatively opposite end thereof, antifriction bearing members supporting the ends of each of said rollers, each bearing member comprising a circular head formed with an opening on its inner side and with a counter-sunk depression at the center of the inner wall of said opening and a disk-like enlargement adjacent to the end of said roller engaging in said opening, the end of said roller being circumferentially reduced and fitting into said depression and antifriction bearing members between said disk-like enlargement and the wall of said opening.

In testimony whereof I affix my signature.

WILLIAM E. WHITEHURST.
